UNITED STATES PATENT OFFICE

FRANK B. TYSON, OF RANDOLPH, KANSAS.

ALTERNATING ROTARY GEARING.

No. 876,112.

Specification of Letters Patent.

Patented Jan. 7, 1908.

Application filed August 21, 1907. Serial No. 389,491.

To all whom it may concern:

Be it known that I, FRANK B. TYSON, citizen of the United States, residing at Randolph, in the county of Riley and State of 5 Kansas, have invented certain new and useful Improvements in Alternating Rotary Gearing, of which the following is a specification.

My invention relates to alternating rotary 10 gearing, and belongs to that class of mechanisms ordinarily employed in connection with washing machines or churns, in which by means of certain associated toothed wheels and other coacting elements a shaft is rotated first in one direction and then in the 15 opposite direction, the driving shaft of the apparatus being always revolved in one and the same direction.

My invention belongs immediately with 20 those contrivances in the class stated which include a frame provided with a rack, the frame and rack rising and falling above and below a suitable driving pinion engaging the rack, and back and forth horizontally as the 25 pinion revolves.

The object of my invention consists in the special construction and arrangement of the parts by which the driven shaft is rotated and reversed, as shown in the accompanying 30 drawings, and it is believed that the labor called for in the operation is materially lessened below that required by such gearing previously used with which I am acquainted.

Figure 1 of the drawings represents a side 35 view. Fig. 2 is a vertical section lengthwise, and Fig. 3 is a top plan view with portions broken away to disclose underlying parts.

Like reference letters are used to designate the same parts throughout the description 40 and drawings.

Upon a suitable base A is supported the bearing B for the driving shaft C which carries the driving pinion D. One end c of the driving shaft projects somewhat beyond the 45 pinion D as illustrated.

The operating frame or rack frame E, having the rack e, as best shown in Fig. 3 is adapted to oscillate vertically and horizontally.

50 The letter F refers to the stops secured on opposite sides of the frame E by the bolts f. The stops F will be again mentioned. The rack frame is pivotally connected at the right hand side as shown on the drawings 55 with an inner frame G by means of the pivot bolt g. The inner frame G does not vibrate

vertically, but, is arranged to revolve in a horizontal direction in contact with the balls H. The run-way for the balls is provided, as best shown in Fig. 2, in part by a flange of 60 inner frame G and by the stationary disk J and annular flange pieces j. The disk is secured as illustrated to the stool a that rises from and, ordinarily, is integrally formed with the base A. To the lower edge of the 65 inner frame is secured the half-circular rack K, that engages the pinion k on the vertical or driven shaft L. That shaft is shown in Figs. 1 and 2.

The remaining elements of my invention 70 are best described in connection with the explanation of the mode of operation. As the driving shaft C is turned, the pinion D engaging rack e turns the frame E, and, consequently, the frame G also, about the 75 stationary disk J as a center. When the pinion has reached the end of the rack the end c of the shaft C encounters the curved guiding-stop F, as explained likewise in Patent No. 844,761 of the United States, issued to me 80 February 19, 1907, and the pinion cannot become disengaged from the rack e, which is, therefore, thrown up and begins a contrary movement above the pinion D. The stop M limits the upward and downward play of the 85 rack frame E, and the side play of that frame with respect to the inner frame G is similarly limited by the vertical stops N borne by frame G. As the rack e passes over the pinion its end is reached and it falls into its original position in which it passes again below the pinion. It is my practice to prevent the hard 90 fall of rack frame E by introducing the spiral spring O around the pivot bolt g in such manner that a portion of the weight of the rack 95 frame is taken up by the spring. The drop of the rack frame is thus in a degree cushioned. As the rack frame and inner frame are operated back and forth, the pinion k and driven shaft L are rotated correspondingly. 100

Having now described the construction of my invention, and explained the mode of its operation, what I claim is—

1. In alternating rotary gearing, the combination with a stationary disk, of an inner 105 frame supported upon the said disk and adapted to revolve about the disk as a center, a rack frame pivotally connected with the said inner frame, a driving shaft, a driving pinion on the driving shaft arranged to engage the rack of the said rack frame, means 110 for limiting the movements of the rack frame

with respect to said driving pinion, a rack borne by the said inner frame, and a driven shaft and pinion engaging the said rack on the said inner frame, substantially as described.

5 2. In alternating rotary gearing, the combination with a stationary disk, of an inner frame adapted to revolve about the disk as a center, balls interposed between the said inner frame and the stationary disk, a rack frame pivotally connected with the said inner frame, a driving pinion on the driving shaft arranged to engage the rack of the said rack frame, means for limiting the 10 movements of the rack frame with respect to said driving pinion, a rack borne by the said inner frame, and a driven shaft and pinion engaging the said rack on the said inner frame substantially as described.

15 3. In alternating rotary gearing, the combination with a stationary disk, of an inner frame supported upon the said disk and adapted to revolve about the said disk as a center, a rack frame pivotally connected with the 20 said inner frame, a spring arranged to press upwardly against the said rack frame, a driving shaft, a driving pinion on the said driving shaft arranged to engage the rack of the said rack frame, curved guiding-stops 25 attached to the said rack frame and disposed to encounter the extended end of said driving shaft, a stop attached to said inner frame and disposed to limit the up and down movements of the said rack frame, a rack borne by the said inner frame, and a driven shaft and pinion engaging the said rack on the said inner frame, substantially as described.

30 movements of the said rack frame with re-

spect to the said driving pinion, a rack borne by the said inner frame, and a driven shaft and pinion engaging the said rack on the said inner frame, substantially as described.

4. In alternating rotary gearing, the combination with a stationary disk, of an inner frame supported upon the said disk and adapted to revolve about the disk as a center a rack frame pivotally connected with the said inner frame, a spring arranged to press 35 upwardly against the said rack frame, a driving pinion, a driving shaft having one end extending beyond said pinion, the driving pinion being arranged to engage the rack of the said rack frame, curved guiding-stops 40 attached to the said rack frame and disposed to encounter the extended end of said driving shaft, a stop attached to said inner frame and disposed to limit the up and down movements of the said rack frame, a 45 rack borne by the said inner frame, and a driven shaft and pinion engaging the said rack on the said inner frame, substantially as described.

In testimony whereof I affix my signature 50 in presence of two witnesses.

FRANK B. TYSON.
